UNITED STATES PATENT OFFICE

JOSEPH J. EHEMANN, SR., AND BENJAMIN F. SINGER, OF LANCASTER, PENNSYLVANIA

SAFETY DEVICE

Application filed March 23, 1929. Serial No. 349,475.

This invention is a safety device for use upon automobiles and its object is to provide a device which will automatically arrest the movement of the vehicle if it should start to travel backward on a down grade. It is the habit with motorists to take all grades in high gear to avoid the labor of shifting gears and it frequently happens that the machine stalls before the top of the hill has been reached and, unless the chauffeur is adept at shifting gears, the machine will travel backward some little distance before its progress can be stopped. Numerous bad accidents have occurred through the lack of means to instantly stop the rearward travel of the machine, and the object of the present invention specifically stated is to provide means which will automatically operate to prevent reverse travel of the vehicle on a down grade. The invention provides means whereby when the reverse travel of the machine is desired the safety device will be thrown into inoperative position and will then not interfere with the desired travel until the gears have been shifted to again provide for forward travel. The invention is illustrated in the accompanying drawings and will be hereinafter first fully described and then more particularly defined in the appended claims.

In the annexed drawings:

Figure 1 is a sectional elevation showing one embodiment of the invention mounted within the transmission case of the vehicle and applied to the motor shaft.

Fig. 2 is an enlarged sectional elevation taken longitudinally of the shaft.

Figs. 3 and 4 are elevations showing the operative and inoperative positions of the device.

Fig. 5 is a detail perspective view of the clutch hub, and

Fig. 6 is a detail perspective view of the roller or dog manipulating element.

In the drawings, the reference numeral 1 indicates the motor casing, the reference numeral 2 indicates the transmission casing and the numeral 3 indicates the gear shifting lever, all of which are of the usual or any approved construction. Within the trans-

mission casing 2 are mounted the usual or any approved transmission gearing 4 whereby the power of the engine may be imparted to the propeller shaft 5 at the desired speed and in the desired direction. The lever 3 cooperates with shifter rods 6 and selector arms 7 in a well known manner to set the gearing for the transmission of the desired speed.

Secured to the rear wall of the transmission casing is a drum or circular case 8 which is disposed concentrically about the propeller shaft 5 and within this case are mounted a plurality of brake rollers or free dogs 9 which are disposed between the annular wall of the case and a hub 10 which is keyed to the shaft, as will be understood upon reference to Fig. 2. The hub 10 is provided in its peripheral surface with a plurality of recesses or chambers 11 in each of which is disposed one of the rollers or free dogs 9 and said recesses or chambers are right angular in form and cooperate with the wall of the casing to form a triangular space within which the respective rollers or free dogs operate. A cap plate 12 is secured upon the forward side of the casing 8 and extends inwardly beyond the inner wall thereof, as shown in Fig. 2, so that it projects over the rollers and thereby prevents the escape of the same. The hub 10 is provided between each two recesses with a lug or projection 13 against which the cap plate rests and in the space thus defined under the cap plate are mounted a plurality of cranks or dog shifting elements 14 which are pivotally fitted to the hub and are adapted to be operated to throw the rollers or dogs into an inoperative position. The cranks 14 are substantially oblong in outline and are pivoted upon the hub near their inner ends by means of pins or studs 15 which are welded or otherwise intimately united with the respective cranks and are adapted to seat in sockets 16 provided therefor in the hub.

At the inner end of the crank is secured an operating pin 17 which projects outwardly from the respective crank, as shown clearly in Figs. 2, 5 and 6, while the outer free end of the crank carries a holder or pair of jaws 18 which are arranged to fit about the re-

spective roller 9 and thereby control the same, it being understood that a portion of the circumference of the roller will project beyond the crank and the holder to ride upon the wall of the case 8. The several pins 17 have their outer free ends engaged in notches or elongated openings 19 in a ring 20 which may be integral with or rigidly secured to one end of a sleeve 21 slidably mounted upon the shaft 5 and provided at its opposite end with an annular groove 22 in which is engaged one of the selector yokes 7. An obliquely disposed slot 23 is formed in the sleeve 21 and through this slot projects a pin or stud 24 secured in the shaft 5, as will be understood.

It will be understood that the casing 8, being fixed to the transmission casing, is stationary at all times and the hub 10, being keyed to the shaft 5, will always rotate with the shaft. Ordinarily the rollers will be held in a position out of contact with the walls of the recesses 11 through the influence of an expansion spring 25 which is coiled around the shaft 5 between the hub 10 and the ring or flange 20 on the sleeve 21 and presses said flange and sleeve forward. Should the forward travel of the machine stop, the device will not be affected unless the machine should at once commence to travel backward, whereupon the reverse travel of the shaft 5 will carry the hub 10 with it so that the obliquely or tangentially disposed walls of the recesses 11 will be brought against the respective rollers 9 and the said rollers caused to travel toward the points of the respective triangular chambers and be thereby caused to bind between the walls of the hub and the wall of the case 8. Reverse travel of the vehicle will, consequently, be automatically prevented. Should it be desired, however, to have the vehicle travel backwardly, the reverse gear is thrown in in the usual manner and this action will carry with it the shifting of the selector arm 7 which is engaged within the groove 22, the result being that the sleeve 21 will be slid rearwardly against the influence of the spring 25 and, as the sleeve is shifted rearwardly, the walls of the slot 23, riding on the stud 24, will cause the sleeve to rotate about the shaft 5, this rotation being imparted directly to the several cranks 14 through the engagement of the pins 17 with the collar 20 so that the cranks 14 will be swung outwardly and rearwardly with respect to the apexes of the several triangular chambers 11 and the rollers 9, consequently, shifted toward the wider ends of said chambers. The rollers will, consequently, be held out of contact with the walls of the chambers and the travel of the machine may then be effected and controlled just as though the safety device was not present. As the reverse gear is shifted back to its normal position, the spring 25 will expand and again act to maintain the safety device to its normal

operative position. When the sleeve 21 is shifted forwardly, it is rotated about the shaft 5 by the engagement of the pin 24 and the cam slot 23 so that the cranks will be rocked in such direction that the rollers are shifted to a position free of the walls of the respective chambers. The strength of the spring 25 is such that it will just hold the rollers in neutral position and maintain such frictional engagement between the pin 24 and the cam slot 23 that the sleeve 21 will rotate with the shaft without sliding along the same but if the shaft should start to reverse the pin and cam slot will act on the sleeve in the same direction as the spring to shift the rollers toward and permit them to assume the braking position. When the machine is thrown in reverse, the rollers are locked in the inoperative position against any tendency of the spring to shift them toward braking position.

From the foregoing description, taken in connection with the accompanying drawings, it will be seen that we have provided an exceedingly simple and compact mechanism which may be applied at a low cost to any vehicle and will operate automatically to prevent undesired backward travel of the vehicle. In applying the invention to vehicles in course of production, the case 8 and the cooperating parts will be arranged within the transmission housing, as shown and described, but in applying the invention to vehicles which are already in use, the parts will be mounted upon the outer side of the end wall of the transmission housing and it may be necessary with some models of cars to elongate somewhat the propeller shaft. It will, of course, be necessary in applying the device to cars now in existence to provide an additional selector arm upon the shifting rod which controls the reverse gear.

Having thus described the invention, we claim:

1. In a safety device, the combination of a circular case disposed concentrically about a driving shaft, a hub keyed to the shaft and disposed within the case and provided in its periphery with a tapered recess forming with the wall of the case a triangular chamber, a roller disposed freely in said chamber, a crank pivoted eccentrically upon the side of the hub and provided at its free end with a holder engaging the roller, a pin projecting from the opposite end of the crank, a sleeve slidably and rotatably mounted upon the shaft, means for shifting the sleeve upon the shaft, said sleeve having a flange in which the pin is seated whereby to rock the crank and shift the roller to an inoperative position, and yieldable means acting on the sleeve to normally hold the same and the roller in an operative position.

2. In a safety device, the combination of a circular case, means for securing the case stationarily about a shaft, a hub secured upon

the shaft within the case and provided in its periphery with a tapered recess forming with the wall of the case a triangular chamber, a free roller in said chamber, a crank pivoted eccentrically upon the side of the hub and engaged at its free end with the roller, a pin projecting laterally from the opposite end of the crank, a sleeve slidably and turnably mounted upon the shaft, a ring carried by one end of the sleeve and engaged with the pin projecting from the crank, the sleeve being provided with a diagonal slot, a stud on the shaft engaged in said slot, means for shifting the sleeve toward the hub, and an expansion spring disposed between the ring and the hub to yieldably hold the crank and the roller normally in an operative position.

In testimony whereof we affix our signatures.

JOSEPH J. EHEMANN, SR.
BENJAMIN F. SINGER.
